UNITED STATES PATENT OFFICE.

OSKAR FINKHAUS, OF WURZBURG, GERMANY, ASSIGNOR TO BOHN & HERBER, MASCHINENFABRIK UND EISENGIESSEREI, OF WURZBURG, GERMANY.

TWO-REVOLUTION PRINTING PRESS.

Application filed November 12, 1925, Serial No. 68,556; and in Germany August 23, 1924.

The frames enclosing the type-bed reciprocating gearing in two-revolution printing presses must withstand considerable force; they must, nevertheless, in order to diminish 5 the inertia forces to which the reversal of motion gives rise, be kept as light as possible. The cast iron frames hitherto used for the purpose are all formed with open ends and consist only of single carrying arms 10 in the form of plates connected with one another.

Such frames in the case of beds that are driven by gear wheels at the points of reversal, have been formed for the purpose of 15 housing the guides and the toothed segments used, as boxes with one side open and with intermediate connecting pieces which are in turn connected by means of bridge pieces above and below with the box-like members. 20 The object of the present invention is to obtain the above enumerated results by means of a different construction of frame which is lighter in weight, requiring a smaller amount of material, and yet obtaining 25 greater strength at the same time, so that a lighter metal of inferior grade may be used and may have the required resisting power to the stresses exerted in different directions in the frame.

According to this invention there is employed for the ends of the gearing enclosing frames for machines with link motion a construction similar to that employed for such frames in machines with gear wheels at the 30 points of reversal. It is characterized thereby that the two ends of the gearing enclosing frame are box-shaped and are formed with an open side. The lower connection of the two end boxes is also formed as a shallow box open at the top, whereas the upper 35 connection is shaped like a plate.

In the drawing a constructional form of the invention is shown by way of example.

Figure 1 shows a longitudinal view of the 40 frame, in section on one side,

Figure 2 shows a section on the line A B of Figure 1,

Figure 3 shows a plan of Figure 1 partly in section,

Figure 4 shows a section of Figure 3 on the line C D.

Figure 5 is a perspective view of the frame looking from the front side thereof.

Figure 6 is a similar view looking from 50 the rear side thereof.

Figure 7 is a longitudinal section taken vertically through the frame, showing the parts of a printing press to be mounted in the frame.

Figure 8 is a horizontal section looking 60 down upon the frame with certain parts therein, and

Figure 9 is a fragmentary vertical sectional view taken substantially midway between the ends of the frame. 65

At the ends of the roller carrying frame, boxes, open at one side, are made up of the lower surface *a*, the front surface *b*, the side surface *c* which carries the crank slide, the inner surface *d* and the upper surface *e*. 70 These boxes are connected as usual above by the support *f* of the upper rack and below by the support *g* of the lower rack and also by a shallow box formed by the lower connecting piece *h* and the two lateral flanges *i* 75 and *j*. In this manner one obtains a casting which is stiff in all directions although using little material, and which is also suitable for construction out of light metal.

The frame is bolted to the type-bed 2 and 80 it carries under the bar *f* the upper rack 3, and above the bar *g*, the lower rack 4. In a bracket 5 secured to the bed of the machine, is mounted a shaft or spindle 11 on the end of which is mounted the gear wheel 6 in such a manner that it can be moved longitudinally of the spindle but cannot rotate therein. Two blocks 6'' secured to the pins 6' engage in a groove 6' of the gear wheel 6. The pins 6' are adjustable in the 85 bracket 5 and moved longitudinally by means of a lever 7 mounted on the bracket 5 and operated by a cam disc 8. In one position on the spindle 11 the gear wheel 6 engages with the rack 3 and in its other position with the rack 4. The gear wheel 6 is provided with a recess 9 in which engages the lower arm 10 of a crank 10' which is keyed to the spindle 11 and carries on its upper arm two rollers 12. In the frame 90 are pivotally mounted two members 13 and 14, Figures 7 and 8, carrying rollers 15 and 16 which project through corresponding openings in the frame. Each of these members is operated by its travel in a cam path 105 17 or 18, as shown in section in Figure 9. The lateral faces *c* carry tracks for the rollers 12.

The spindle 11 and therefore the gear wheel 6 rotates continuously. In the posi- 110

tion shown in Figure 7, the gear wheel 6 will continue to travel on the curve 23, and then on the vertical line 24, the member 14 and the lever 7 coming into operation, so that the wheel 6 will subsequently engage with the rack 4, until it reassumes the position shown in Figures 7 and 9. 35

5 I claim:

1. A frame for enclosing type-bed reciprocating gearing of two-revolution printing presses, comprising an elongated body part 40 within which the mechanism may reciprocate, and box-shaped end portions for said body part of the frame, both the body part and the end portions being open at one side of the frame to provide upper and lower flanges, the upper flange being offset beyond the lower flange. 45

10 15 20 25 30 35 40 45 50 55

2. A frame for enclosing type-bed reciprocating gearing of two-revolution printing presses, comprising an elongated body part 50 for accommodating the reciprocating mechanism, said body part provided with vertical reinforcing webs spaced from the opposite ends thereof and providing between the webs and said ends box-shaped end portions, said box-shaped ends and the body part having a closure plate portion at their upper side. 55

25 30 35 40 45 50 55

In testimony whereof I have affixed my signature.

OSKAR FINKHAUS.
